United States Patent Office.

JOHN OTTO DONNER, OF JERSEY CITY, NEW JERSEY.

Letters Patent No. 96,900, dated November 16, 1869.

IMPROVEMENT IN VACUUM-PANS AND SIMILAR APPARATUS.

The Schedule referred to in these Letters Patent and making part of the same.

To all whom it may concern:

Be it known that I, JOHN OTTO DONNER, of Jersey City, in the county of Hudson, and State of New Jersey, have invented a new and useful Improvement in Vacuum-Pans, applicable also to other purposes, of which the following is a full, clear, and exact description, reference being had to the accompanying drawing, forming part of this specification, and which represents a sectional elevation of a vacuum-pan, with my improvement applied thereto.

While applicable to a variety of purposes, in which it is desirable to prevent the escape of fluid or solid or soluble matter, along with steam or vapor generated within a boiler or other vessel, it will suffice to describe this improvement, in connection with a vacuum-pan, as used in the manufacture of sugar, for which purpose my invention is mainly designed.

In such connection, therefore, the improvement consists in a novel construction of trap, arranged within the pan, below the pipe that carries off the vapor, whereby the sugar is not only restrained from boiling over into the overflow, where that device is used, but saccharine solution, carried up along with the vapor, is prevented from passing off by the escape-pipe to the condenser, and thus a large percentage of loss or waste avoided.

Referring to the accompanying drawing—

A represents a vacuum-pan, which may be of the ordinary construction used in the manufacture of sugar.

B is the vapor-pipe, leading from said pan either to the usual or any suitable overflow, or directly to the condenser.

C is a funnel-shaped rim, or annular projection, to the under side of the top of the pan, of larger diameter than the escape-pipe B, that occupies a concentric position, or thereabout, to it.

This rim C should be of a tapering or hollow curvilinear form on its exterior, swelling outward in an upward direction.

Arranged immediately below this funnel-shaped rim C, is a cup-shaped vessel or device, D, of larger diam-

eter than the lower end of the rim C, so as to leave an annular space, b, between the upper edge of said cup D and lower end of the rim C.

A return-pipe, e, leads from the bottom of this cup back into the pan A, or elsewhere, as may be desired.

In the operation of this trap, as formed by the funnel-shaped rim C and cup D, the vapor, in rushing with an accelerated velocity to and through the escape-pipe B, is restrained from doing so in a straight line, by being caused to first pass through the annular opening b, and said vapor in its way, at a certain velocity, through this opening, and carrying along with it saccharine solution, which, were it not for the trap, would pass off into the overflow or outward to the condenser, is here separated, the funnel-shaped rim C causing the vapor and liquid particles or saccharine solution carried up with it to assume a circular, whirling action, following the tapering or curved exterior of said rim, the consequence of which is that the heavier particles, such as the mist-like particles of the saccharine solution, having a greater momentum than the vapor, will be made to keep the direction in which they have been diverted by the rim C, and be deposited within the cup D, from whence they may be returned by the pipe e to the pan, or be conveyed to any other suitable place of deposit, while the vapor, separated by such precipitation of the saccharine solution within the cup D, will alone pass off by the escape-pipe B.

What is here claimed, and desired to be secured by Letters Patent, is—

The combination and arrangement, with the vacuum-pan or vessel A, and relatively to the escape-pipe B, for the vapor generated within said vessel, of the tapering or curved funnel-shaped rim C and cup D, constructed to leave an annular opening, b, between them, substantially as and for the purpose or purposes herein set forth.

J. O. DONNER.
